UNITED STATES PATENT OFFICE.

CHARLES H. BAYLEY, OF BOSTON, MASSACHUSETTS.

SIGN.

SPECIFICATION forming part of Letters Patent No. 432,968, dated July 29, 1890.

Application filed January 28, 1890. Serial No. 333,369. (No model.)

To all whom it may concern:

Be it known that I, CHARLES H. BAYLEY, of Boston, county of Suffolk, State of Massachusetts, have invented an Improvement in Rotatable Signs for Street-Cars, of which the following description, in connection with the accompanying drawings, is a specification, like letters and figures on the drawings representing like parts.

10 This invention has for its object to provide a street-car with a rotatable illuminable sign adapted to be lighted by electricity.

In accordance with my invention a frame having glass or translucent or transparent 15 sides is mounted upon a street-car so as to be rotated when desired, to thereby bring to the front a side containing the name of the street or district or destination of the car, or to convey by letters or words other information.

20 One of the journals of this frame is hollow, and through it is led the necessary wires to enable an incandescent lamp to be energized or lighted.

My invention consists, essentially, in the 25 combination, with a revolving frame-like sign having a hollow journal, of an incandescent electric lamp, the wires leading to the lamp being passed through the said hollow journal, substantially as will be described.

30 Figure 1 in side elevation represents a sign embodying my invention; Fig. 2, a section in the line *x*; Fig. 3, an end view looking at the sign from the left in Fig. 1.

Referring to the drawings, A is supposed to 35 be part of the roof of a street-car of any usual construction. On the roof are suitable bearing-stands B B', the stand B being shown as receiving the journal *a* of a hollow sign C, having glass or other transparent or trans-

lucent sides *c c*, on which will, in practice, be 40 displayed, by suitable letters or characters, the legend to be told by the sign, as a street or name, these sides being adapted by usual means to be slid out and into the grooves for receiving them whenever desired. The journal *a'* of the hollow sign is hollow, and as 45 shown is fixed in or with relation to the stand B, and the journal has a movable collar *a²*, held in place by a set-screw 2, the said collar acting against a washer or plate *a³* at 50 that end of the sign, whereas the journal *a*, which rotates, is connected to the plate *b*, which is fixed to the cage.

As herein shown, the incandescent lamp is attached to the inner end of the journal *a'*, 55 which is extended into the said sign as far as desired, preferably to about the center of its length.

The wires *d d*, to energize the usual filament in the lamp, are carried through the 60 hollow journal *a'*.

The lamp is accessible by partially withdrawing one of the sides of the sign or by opening a part of the sign in any desired way.

I claim—

The rotatable illuminable sign having a 65 hollow journal, combined with an incandescent electric lamp located within the said sign, and with wires leading thereto through the said journal, substantially as described.

In testimony whereof I have signed my name to this specification in the presence of two subscribing witnesses.

CHARLES H. BAYLEY.
